UNITED STATES PATENT OFFICE.

BENVENUTO GIANESE, OF GENOA, ITALY.

DUPLEX DAVITS APPARATUS.

1,134,118.

Specification of Letters Patent.

Patented Apr. 6, 1915.

Application filed July 24, 1913. Serial No. 780,862.

To all whom it may concern:

Be it known that I, BENVENUTO GIANESE, a subject of the King of Italy, residing at Genoa, gentleman, whose post-office address is 80 Corso Firenze, Genoa, Italy, have invented a new and useful Duplex Davits Apparatus, of which the following is a specification.

The object of my present invention is to provide an improved device by which in one rapid operation carried out by a limited crew, and even one person, two boats placed the one above the other, on or outside board, may be lowered without going to the trouble of turning the davits home and hauling in the tackles, as was necessary hitherto for lowering a second boat after the first with the ordinary means.

My new device comprises two additional davits with circular movement coupled to the ordinary davits in a different way the one from the other, so that it is possible to operate the whole series comprising two double davits by the mechanical action imposed only to one of them by a worm gear and wheel.

In order that my invention may be more clearly understood I am now going to describe same with reference to the annexed drawings in which—

Figure 1 is a side view showing a series of boat's davits, Fig. 2 a horizontal projection of davits with boats, Fig. 3 a diagrammatical horizontal view showing the position of the davits on quarter-deck, Figs. 4 and 5 are groups of davits with the operative organs in section; Fig. 6 is a plan view of Fig. 5; Fig. 7 a detail view showing the connection of the additional davit to the ordinary one, Fig. 8 a plan view of worm gear and wheel, Fig. 9 a section on line $a-a$ of Fig. 4, Fig. 10 a section on line $b-b$ of Fig. 4, Figs. 11 and 12 ball bearings for operating the additional davit, and Fig. 13 is a detail sectional view of one of the base supports for the main davits.

In the present case both the ordinary and additional davits are supposed to be equipped with their tackles, the top boat being the first to be swung off board and lowered, the additional davits with the tackles thus being in perpendicular position over the second or bottom boat to be suspended so that as soon as the first boat is disengaged from the tackles the second boat is

raised from the supporting deck, swung outward, and then lowered down.

If it is desired to keep boats suspended outside board both the first and second davits may be used to support the boats at all times while not in use. In this case the operation of lowering is almost instantaneous, as all of the boats may be hooked to the tackles and kept ready or suspended under the davits.

Fig. 1 of the drawings shows a series of davits comprising the ordinary ones $N N'$, which are journaled in bearings n and n' , and two additional ones $A A'$. One of the bearings n' is shown in detail in Fig. 13. The additional davit A on which the supports $-s-$ $-s'$ are fixed is coupled to davit N by inserting the latter through bearing openings provided for the purpose in the supports. When the said davit A is coupled to N it is capable of freely swinging about N , in the same way as, for instance, a double armed crank loose on its shaft is capable of turning about the latter. Therefore the supports $-s-$ $-s'$ while fixed to davit A are loosely connected to davit N , so that these davits are capable of moving and turning independently of each other. Beneath the bottom supports $-s-$ (Fig. 4) and within a groove provided in each of the two half steel rings Figs. 11 and 12, fitted ferrule-like to davit $-N-$, are placed balls of tempered and nickeled steel. Davit A which with support $-s'$ bears on the half-ferrule above the balls is capable of rotating, with minimum friction and thus requires little effort in operating it. Support $-s-$ only serves as guide and point of support.

In order to avoid useless friction and facilitate the rotary movement of the ordinary davits $N N'$, in the main or bottom support H (see also Fig. 4) a plate of tempered steel is placed, having a central point or spike in which bears the whole weight of davits $N N'$. The hollow space is filled, when mounting the davits, with tallow or fat. The additional davit A' , on the other hand, is adjustably mounted upon the ordinary davit N' , but is adapted to be rigidly coupled to the davit N' . In this case the two supports $-r-$ $-r'$ of davit A' are so fixed to davit N' as to form a rigid whole, where the arms of the two davits A' and N' form an angle to each other which is generally of 90° if the two lifeboats to be han-

dled are superposed, whether both are to be swung home, *i. e.* inside board, or one suspended outside board and the other inside board. The said two arms of the davits 5 may, on the other hand, form an angle of 45°, or a little greater, to each other if the boats are arranged partly overlapping and also in case of complete superposition. The said davit A' is always coupled to davit N' 10 at a fixed optional angle which depends from the position of the boats being more or less overlapping. To the ordinary davit N' a gearing I is coupled, which is operated by a worm gear —v— and crank M on standard C fixed on the quarter-deck (details shown in Fig. 5).

—b— is a double bridled arm fixed on the one hand to the screw threaded standard while on the other hand at —d— it allows 20 davit N' to move freely. The said double bridled arm —b— serves for keeping the distance between the axes of standard C and davit N' unvaried even under the action of an eventually required higher stress or effort.

Fig. 2 is a horizontal projection or top view of the davits with two superposed boats, the top one of which is an ordinary lifeboat while the lower one is a boat of the 30 Engelhardt type. Davit A which is loosely movable about davit N may be brought into more convenient and ready position on board for hooking the tackles, the arms of davits A and N then forming an angle 20° to 30° to each other, and consequently davits A and n, may take the positions shown in dotted lines —p— —p— or —p'— —p''— which former position is also shown in Fig. 3, direction P I (inboard or home position 40 of davits).

Fig. 2 shows how a single man by operating in two movements the crank M may swing out two boats, controlling, when swinging the boats outside board, the whole 45 series of davits, as by turning crank M davit N' is swung out, and therewith the suspended part of the top lifeboat. The opposite davit, which is capable of free and independent movement, follows the movement 50 of the boat imparted to it by davit N' through crank M, worm —v— and gearing I. When davit N' has been brought into such a position as to lower the boat, also davit N will be outside board, being obliged 55 to follow the movement of the boat. The boat is thereby almost entirely outside board by the mechanical movement imparted only to davit N'. After the first boat is lowered the davits N and N' are outside board in the 60 position taken by them for the carried-out operation. The tackles belonging to these davits remain hanging outside board, and

it is not necessary to haul them in. Davit A' which in Fig. 2 is fixed at an angle of about 85° to the arm of davit N' has been 65 brought, by the preceding operation, to the new position A'' adapted for hoisting up the lower boat which is resting upon the deck, thereby moving the perpendicularly suspended tackle to the point of attachment. 70 Of course, also from the opposite side the davit A which also may be in one of the positions —p— —p—, —p'— —p''— passes to operative position when the block has been hooked on to the point of attachment 75 and suspension owing to the fact that this davit is free for movement independently of davit N.

After the lower boat has been hoisted up, crank M is turned farther thereby acting on the worm gearing. While davit A' from position A'' is moved to position A''', 80 davit N' passes to position N'', while davit A (which follows the movement of the boat imparted to the latter by manual operation 85 of davits A' and N') passes first to position and direction —p'— and then to position and direction —p''—. Davit N which has become disengaged by the preceding operation and is now useless for the second operation, is in position T, Fig. 2.

Fig. 3 shows diagrammatically the position of the davits on the quarter-deck. The position in direction and side P I is the one 95 occupied by the davits when the lifeboats are home, while position P E is the one occupied by the davits outside board after the first boat has been lowered and the second is being lowered.

Having now fully described my said invention and the manner in which the same is to be performed, I declare that what I claim as my invention is:

An improved boat's davits device comprising a pair of main davits mounted for oscillation on vertical axes, means by which one of the main davits may be operated, an additional davit pivotally connected to the other main davit for independent movement on a vertical axis, an additional davit mounted upon the operable main davit for horizontal adjustment angularly with respect to the last named main davit, and means for securing the last named additional davit fixedly in adjusted position upon the main davit supporting the same.

In testimony whereof I have signed my name to this specification in the presence of two subscribing witnesses.

BENVENUTO GIANESE.
